Primary Examiner — Ian Simmons*Assistant Examiner* — Carissa C Fitts(57) **CLAIM**

The ornamental design for a container light, as shown and described.

DESCRIPTION

FIG. 1 is a front side perspective view of my container light, shown in reference inside a container;

FIG. 2 is a front perspective view of the light of FIG. 1;

FIG. 3 is a front elevation view thereof;

FIG. 4 is a rear elevation view thereof;

FIG. 5 is a top plan view thereof; and

FIG. 6 is a bottom plan view thereof;

FIG. 7 is a left side elevation view thereof; and,

FIG. 8 is a right side elevation view thereof.

The broken line showing is for illustrative purposes only and forms no part of the claimed design.
